Primary Examiner — Darlington Ly(74) *Attorney, Agent, or Firm* — Rosenberg, Klein & Lee(57) **CLAIM**

The ornamental design for a tool adapter, as shown and described.

DESCRIPTION

FIG. 1 is a top, front, and right side perspective view of a tool adapter showing my new design;

FIG. 2 is a front elevational view thereof;

FIG. 3 is a rear front elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom, front, and left side perspective view thereof; and,

FIG. 9 is a top, front, and right side perspective view thereof with an exemplary application.

The broken line showing in FIG. 9 is provided for the purpose of illustrating environmental structure, of which forms no part of the claimed design.

1 Claim, 8 Drawing Sheets(56)
